UNITED STATES PATENT OFFICE.

CARL G. OLSON, OF CHICAGO, ILLINOIS. ASSIGNOR TO ILLINOIS TOOL WORKS, OF CHICAGO, ILLINOIS, A CORPORATION OF ILLINOIS.

HOB-GRINDING MACHINE.

Application filed May 1, 1926. Serial No. 105,966.

My invention relates to machines for grinding hobs and like articles, and the object of the invention is to simplify machines of this class and also to provide a construction which will make for accurate work and for ease of adjustment and manipulation by the operator. A further object is to provide automatic means for making certain adjustments and corrections in the operation of the machine. I accomplish these objects by the mechanism illustrated in the accompanying drawings in which

Figure 1 is a front elevation of the machine partly in section.

Figure 2 is a top plan view partly in section showing the tool holder or grinder head and associated parts.

Figure 3 is a detail view illustrating the manner in which the grinding wheel may be reversed to grind opposite sides of the hob teeth.

Figure 4 is an end elevation looking toward the left in Figure 1.

Figure 5 is a sectional elevation showing the tool holder and associated parts. In this view the tool holder is shown to be adjusted to the center of the sector plate or quadrant.

Figure 6 is an elevation looking toward the left of Figure 5. This view is partly in section.

Figure 7 is an elevation looking toward the left of Fig. 6.

Figure 8 is similar to Figure 1 but shows the grinding head reversed to grind the opposite side of the hob teeth.

Figure 9 shows a modified form of tool holder and support. In this form the tool holder is automatically raised or lowered as it is reversed to bring the grinding wheel in proper position on the hob tooth.

Figure 10 is a diagram illustrating the application of the machine to hobs having small teeth. The action illustrated is in accordance with the construction shown in Figures 1 to 8 inclusive.

Figure 11 is a diagram illustrating the application of the machine to hobs having larger hob teeth and where a correction is necessary in reversing from one side of the tooth to the other in a straight gash hob. The diagram illustrates the operation of the modified form shown in Figure 9.

Like numerals denote like parts throughout the several views.

Referring first to the form shown in Figures 1 to 8 inclusive, the hob 15 is mounted upon a spindle 16, journaled in a bearing 17, mounted in a rocking frame 18. The outer end of the spindle is in the form of a lead screw 20 which works within a nut 22 mounted in the said rocking frame. The lead of the screw is the same as in the hob to be ground. Thus spindle 16 has two bearings, one of which is in the form of a lead nut, and it is evident that when the spindle rotates it will simultaneously move in an axial direction in accordance with the helical lead of the hob teeth.

Spindle 16 is rotated by means of a gear 24 meshing with a wide face pinion 26 which has a fixed axis in the main frame or bed 27. It is rotated by means of gearing including the gear 28 shown at the left of Figure 1. The rocking frame 18 oscillates back and forth upon the main frame to bring the hob toward and from the grinding wheel 30 to produce the necessary relief in the hob teeth. The mechanism for accomplishing this purpose need not be described for it is not intimately concerned with my present invention and furthermore is described and shown in detail in my prior Patent No. 1,575,713.

Referring now to the parts more closely concerned with my present invention:

A slide 32 is mounted on the main frame 27 and is controlled by a feed screw 34 provided with a handle 35 in the usual manner. Transversely mounted on slide 32 is a second slide 36 adjustable by means of a screw 37 provided with a knurled head 38. These slides 32, 36 and their associated parts constitute a tool post or compound rest. On the upper slide 36 is an element 40 which for convenience may be termed a "sector plate." It carries the grinder head which will presently be described. Said plate is rockable on slide 36 in order that the grinder wheel may be adjusted to the helix angle of the hob to be ground. It has, on the bottom, two rockers 42 which rest in channels 44 in the slide as best shown in Figures 4 to 7. The sector plate is held in the position to which it is adjusted by means of an anchor bolt 46 best shown in Figures 5 and 6. This bolt is secured to slide

36 and at the upper end has a nut 48 which screws down upon a washer 50. Said washer has a cylindrical under surface concentric with the rockers 42 and with the axis of the 5 grinding wheel when the latter is in the centralized position shown in Figures 5 and 7. The washer fits in a correspondingly curved countersink 51 formed in the top of the sector plate, and the result is that said plate and 10 the parts carried thereby may be tilted to various degrees to harmonize with the helix angle of the hob which is being ground. This adjustment also provides for the grinding of right hand or left hand hobs. In order to determine the angle of tilt the sector plate is 15 provided with a graduated scale 53 adapted to cooperate with a center line 54 marked on slide 36 as shown in Figure 7.

At the center of curvature of the sector 20 plate 40 is a stud 52 shown at the lower left corner of Figure 6 and elsewhere. This forms a pivot for the grinder head presently to be described. It will be observed that this stud is approximately vertical, the obliquity depending upon the angle to which the sector plate is tilted for adjustment to the helix angle of the hob. The dot and dash circle in Figure 6 indicates the position of the hob and it will be noted that the axis of the stud 52 30 would, if produced, pass near but outside of said circle.

The base 58 of the grinder head is apertured to receive said pivot pin or stud 52. It is held yieldingly in close contact with the 35 sector plate by means of a leaf spring 60 which underlies the head of the pin and presses down upon the said grinder head base. The base of the grinder head is arched so as to clear the anchor bolt 46 as shown in Figure 6. The outer end of the said base rests slid- 40 ingly upon the upper peripheral surface of the sector plate and has a depending flange 62 for engaging the outer rim thereof. The parts are beveled in order to hold the base 45 element firmly seated. This action is promoted by a block 64 which engages the outer edge of the sector plate and is backed up by a set screw 66. A locking pin 68 is carried by the grinder head base and is adapted to drop 50 into sockets 70 formed at different points in the sector plate. These sockets are distributed in such manner as to hold the grinding wheel in contact with the sides of the hob teeth, and ordinarily there are sufficient of 55 these sockets to correspond to the usual pressure angles employed in the making of hobs.

The grinder head base has formed upon it a bearing or holder 71 for a "quill" 72 in which the grinder wheel spindle 74 is rotatably 60 mounted. This spindle is driven by a sheave 76 and belt 78, or any other suitable means. A cap 80 forms the upper part of the holder for the quill, and this cap is normally held down in place by latches 82.

65 The machine is equipped with a tool dress-

ing device which, according to the illustrated design, has a body 84 equipped with two rings 86 which encircle the quill at either end of the quill holder. Consequently the dressing device is rotatable about the axis of the quill 70 holder. One of the rings is split and is clamped in position by means of a clamping bolt 88. A housing 90 is secured to the body 84 of the dressing device and this forms a 75 guide for a sliding bar 92 which is provided with a diamond point 93 for dressing the grinding wheel. Bar 92 is reciprocated when necessary by an operating handle 94. These parts need not be herein described in detail, as they are shown in the pending application 80 of Charles J. Irwin for truing device, Serial No. 622,275. By thus making the dressing device rotatable about the axis of the grinder spindle it may be rotated to different positions where it will be least in the way of the operator and of the hob and adjacent parts of the machine. In other words, it may be swung out of the way without necessitating actual removal from the machine, and it is operative in any of its positions with equal results. 90

In practice, the parts will be adjusted as shown in Figures 1 to 8 inclusive. The sector plate 40 will be tilted to bring the grinding wheel to the proper helix angle and the grinder head will be adjusted about the pivot pin 52 95 to the angle called for by the pressure angle of the hob teeth. The operator then starts the machine which causes the grinder to revolve and causes pinion 26 to rotate the gear 24 and spindle 16. Thus the work rotates and simultaneously moves axially and it also oscillates toward and from the grinding wheel in the manner described in my above mentioned Patent 1,575,713. After the hob teeth have 100 been ground upon one side the grinder head 105 is reversed by rotating it about the axis of the pivot pin 52. For this purpose the locking pin 68 is lifted from one of the sockets 70 and replaced in another one near the opposite end of the sector plate. This reverses the position 110 of the grinding wheel from the full line position shown in Figure 3 to the dotted line position shown in that figure. 115

While it may not be essential, I consider it desirable to so adjust the machine in the beginning that the pivotal axis of the grinding head will pass through the point *a* shown in Figure 3. This point lies in a plane *b* which is perpendicular to the axis of the hob and in the illustrated case this plane is at the center 120 of a tooth. The point *a* also lies on the axis of the grinding wheel indicated by the line *c* Figure 3. It is also at a somewhat greater distance from the hob axis than the radius of the hob. 125

The reversing of the grinding wheel will theoretically introduce an error into the work, but where the hob teeth are comparatively small this error will be so small as to be negligible. This fact is illustrated in Fig- 130

ure 10. The hob tooth 100 has a front line 101 which, being parallel to the axis of the hob as in a straight gash hob, is not at right angles to the sides of the tooth. The grinding wheel 5 should start tangentially at the front of the tooth, but when adjusted, as shown, it will be a little above the front of the tooth when at one side, as indicated by the full line circle h and will be a little below the front line of the 10 tooth when on the opposite side as shown by the dot and dash circle h' .

In grinding hobs having larger teeth this error cannot be neglected and an adjustment should be made, and I have provided for such 15 adjustment by the mechanism shown in Figure 9. In this case the base 58 of the grinder head is fastened to a screw 110, which works in a threaded boss 111, and the result is that when the grinder head swings from 20 one angular position to the opposite one to grind the opposite side of the tooth the grinding wheel will be automatically lowered or raised, as the case may be. To harmonize with this movement the outer periphery 112 of the sector plate is of helical form. The 25 operation is illustrated in Figure 11 where the larger tooth 114 has a straight front 115. The grinder wheel when in the position shown by the circle H will be tangential to the side 30 of the tooth at the front end, and when reversed to the dot and dash position H' will be automatically raised and become tangential to the opposite side of the tooth at the front thereof. Thus the type of machine shown 35 in Figure 9 automatically adjusts itself vertically to raise and lower the grinding wheel and bring it tangential to the sides of the hob teeth at the front thereof.

Having thus described my invention what 40 I claim as new and desire to secure by Letters Patent is:

1. A hob grinding machine having a hob 45 spindle, a reversible grinder head for holding the grinding wheel in contact with the hob, and means for rotating the hob and simultaneously causing relative travel between the hob and the grinding wheel in accordance with the lead of the hob and a relative bodily movement radially of the hob in accordance 50 with the relief in the hob teeth, said grinder head being pivoted about an axis approximately perpendicular to a plane whose position is determined substantially by the hob axis and the grinding wheel axis.

2. A hob grinding machine having a horizontal hob spindle, a reversible grinder head for holding the grinding wheel in contact with the hob, and means for rotating the hob and simultaneously causing relative travel between the hob and the grinding 60 wheel in accordance with the lead of the hob and a relative bodily movement radially of the hob in accordance with the relief in the hob teeth, said grinder head being pivoted about an axis passing through the axis of 65

the grinding wheel substantially at right angles thereto, the grinding wheel axis being oblique to the hob axis both in a vertical and a horizontal direction.

3. A hob grinding machine having a hob 70 spindle, a reversible grinder head for holding the grinding wheel in contact with the hob, and means for rotating the hob and simultaneously causing relative travel between the hob and the grinding wheel in accordance 75 with the lead of the hob and a relative bodily movement radially of the hob in accordance with the relief in the hob teeth, said grinder head being pivoted about an axis substantially perpendicular to a plane 80 determined approximately by the hob axis and the grinding wheel axis, the axis of the grinder head being spaced from the hob axis an amount approximately equal to the radius of the hob.

4. A hob grinding machine having a horizontal hob spindle, a reversible grinder head for holding the grinding wheel in contact with the hob, and means for rotating the hob and simultaneously causing relative travel 90 between the hob and the grinding wheel in accordance with the lead of the hob and a relative bodily movement radially of the hob in accordance with the relief in the hob teeth, said grinder head being pivoted about an axis approximately vertical and substantially perpendicular to a plane determined 95 approximately by the hob axis and the grinding wheel axis, the axis of the grinder head being spaced from the hob axis an amount approximately equal to the radius of the hob, the axis of the grinding wheel being oblique to the axis of the hob.

5. A hob grinding machine having a hob 105 spindle, a grinder head for holding the grinding wheel in contact with the hob, means for rotating the hob and simultaneously causing relative travel between the hob and the grinding wheel in accordance with the lead of the hob and a relative bodily movement radially 110 of the hob in accordance with the relief in the hob teeth, said grinder head being pivoted about an axis lying approximately in a plane which is perpendicular to the axis of rotation of the hob but tilted with respect to it to a degree equal to the helix angle of the hob whereby the position of the grinder wheel may be reversed and thus act first upon one 115 side of the hob teeth and then upon the opposite side.

6. A hob grinding machine having a hob 120 spindle, means for rotating it and simultaneously causing it to travel axially, a grinding wheel, a reversible grinder head for supporting the wheel, a support for the grinder head, the grinder head being angularly adjustable on the support about an axis substantially perpendicular to and passing through the grinding wheel axis and passing outside of the hob, whereby the grinder head may be 125 130

reversed to bring the grinding wheel into contact with the opposite sides of the hob teeth, and means for causing relative movement between the hob and the grinding wheel radial-
5 ly of the hob in accordance with the relief in the hob teeth.

7. A hob grinding machine having a hob spindle, means for rotating it and simultaneously causing it to travel axially, a grinding wheel, a grinder head for supporting the wheel, a support for the grinder head, the grinder head being angularly adjustable on the support about an axis substantially perpendicular to and passing through the grinding wheel axis whereby the grinder head may be reversed to bring the grinding wheel into contact with opposite sides of the hob teeth, and means for securing the grinder head in two different positions on its support, both
15 of which are oblique to the axis of the hob.

8. A hob grinding machine having a hob spindle, means for rotating it and simultaneously causing it to travel axially, a grinding wheel, a grinder head for supporting the wheel, a support for the grinder head, the grinder head being angularly adjustable on the support about an axis substantially perpendicular to and passing through the grinding wheel axis whereby the grinder head may be reversed to bring the grinding wheel into contact with opposite sides of the hob teeth, the axis of adjustment of the grinder head being spaced from the hob axis a distance at least as great as the radius of the hob, and
30 means for causing relative bodily movement between the hob and the grinding wheel in accordance with the relief in the hob teeth.

9. A hob grinding machine having a horizontal hob spindle, means for rotating it and causing it to simultaneously travel axially, a substantially horizontal sector, a grinder head pivotally mounted on said sector about an axis which is approximately vertical but tilted in accordance with the helix angle of
45 the hob, the grinder head pivot passing outside of the body of the hob, a grinder wheel supported in the grinder head and having its axis of rotation substantially horizontal, and means for causing relative movement between the hob spindle and the grinding wheel in a direction radial to the hob to produce relief in the hob teeth.

10. A hob grinding machine having a horizontal hob spindle, means for rotating it and causing it to simultaneously travel axially, a substantially horizontal sector, a grinder head pivotally mounted on said sector about an axis which is approximately vertical but tilted in accordance with the helix angle of the hob, the grinder head pivot passing outside of the body of the hob, a grinder wheel supported in the grinder head and having its axis of rotation substantially horizontal, means for causing relative movement between
60 the hob spindle and the grinding wheel in a

direction radial to the hob to produce relief in the hob teeth, and means whereby the sector may be tilted to different angles to correspond with the different helical leads of the hob teeth.

11. A hob grinding machine having a hob spindle, a grinder head for holding the grinding wheel in contact with the hob, means for rotating the hob and simultaneously causing relative travel between the hob and the grinding wheel in accordance with the lead of the hob and a relative bodily movement radially of the hob in accordance with the relief in the hob teeth, said grinder head being pivoted about an axis approximately perpendicular to a plane determined by the hob axis and the grinding wheel axis whereby the grinding wheel may be reversed to grind the two sides of the hob teeth, and means for automatically raising and lowering the grinder head when it
70 is reversed.

12. A hob grinding machine having a hob spindle, a grinder head for holding the grinding wheel in contact with the hob, means for rotating the hob and simultaneously causing relative travel between the hob and the grinding wheel in accordance with the lead of the hob and a relative bodily movement radially of the hob in accordance with the relief in the hob teeth, a sector for supporting the grinder head, said sector being tilted with respect to the hob axis in accordance with the helix angle of the hob, the grinder head being rotatable upon said sector about an axis perpendicular to the plane of the sector and
90 spaced from the hob axis whereby the grinding wheel may be reversed to grind opposite sides of the hob teeth, and means for fixing the grinder head in different angular positions on the sector corresponding to the reverse positions of the grinding wheel.

13. A hob grinding machine having a hob spindle, means for rotating it and simultaneously causing it to travel axially, a grinding wheel, a grinder head for supporting the wheel, a support for the grinder head, the grinder head being swiveled on the support about an axis substantially perpendicular to and passing through the grinding wheel axis, and means for securing the grinder head to its support at two different positions at equal distances from a plane perpendicular to the hob axis and passing approximately through the swivel axis, whereby the grinding wheel may be reversed and thus caused to
110 grind opposite sides of the hob teeth.

14. A hob grinding machine having a hob spindle, a grinder head for holding the grinding wheel in contact with the hob, means for rotating the hob and simultaneously causing relative travel axially and also toward and away from the grinding wheel in accordance with the relief in the hob teeth, said grinder head being swiveled about an axis substantially perpendicular to the grinding
125

wheel axis, and means for securing the grinder head in two different positions approximately at equal angular distances from a plane perpendicular to the hob axis and passing approximately through the swivel axis whereby the grinding wheel may be reversed to grind opposite sides of the hob teeth.

15. A hob grinding machine having a hob spindle, a grinder head for holding the grinding wheel in contact with the hob, and means for rotating the hob and simultaneously causing relative travel between the hob and the grinding wheel in accordance with the lead of the hob and a relative bodily movement 10 radially of the hob in accordance with the relief in the hob teeth, a support capable of movement parallel and transverse to the hob axis, a sector plate mounted on said support and tiltable with respect to the hob axis in accordance with the helical lead of the hob, the grinder head being swiveled to said sector plate about an axis perpendicular thereto whereby the grinder head may be reversed to

bring the grinding wheel into contact with opposite sides of the hob teeth. 25

16. A hob grinding machine having a hob spindle, a grinder head for holding the grinding wheel in contact with the hob, means for rotating the hob and simultaneously causing relative travel between the hob and the grinding wheel in accordance with the lead of the hob and a relative bodily movement radially of the hob in accordance with the relief in the hob teeth, said grinder head being pivoted about an axis lying approximately in a plane 30 which is perpendicular to the axis of rotation of the hob but tilted with respect to it to a degree equal to the helix angle of the hob whereby the position of the grinder wheel may be reversed and thus act first upon one side of the hob teeth and then upon the opposite side, the grinder head axis passing outside of the hob. 35

In witness whereof, I have hereunto subscribed my name.

CARL G. OLSON.
